UNITED STATES PATENT OFFICE.

GEORGE HRIB, OF SIMPSON, WEST VIRGINIA.

AEROPLANE.

1,385,786.

Specification of Letters Patent. Patented July 26, 1921.

Application filed December 16, 1920. Serial No. 431,291.

To all whom it may concern:

Be it known that I, GEORGE HRIB, a citizen of Czechoslovakia, residing at Simpson, in the county of Taylor and State of West Virginia, have invented certain new and useful Improvements in Aeroplanes, of which the following is a specification.

This invention relates to certain new and useful improvements in aeroplanes and has 10 particular reference to an improved means for supporting and driving an auxiliary overhead propeller which may be either located to be serviceable in retarding the descent of the aeroplane or to provide a secondary 15 or auxiliary propeller for causing forward movement of the aeroplane.

With this general object in view and others that will become apparent as the nature of the invention is better understood, 20 the same consists in the novel form, combination and arrangement of parts hereinafter more fully described, shown in the accompanying drawings and claimed.

In the drawings, wherein like reference 25 characters indicate corresponding parts throughout the several views,

Figure 1 is a side elevational view of an aeroplane equipped with one form of auxiliary propeller supporting and driving 30 mechanism constructed in accordance with the present invention,

Fig. 2 is a view of a portion of the device shown in Fig. 1 drawn on a larger scale and with the body of the aeroplane in longitudinal section to reveal parts within said body,

Fig. 3 is a rear elevational view of the device shown in Fig. 2 with parts broken away to reveal other parts,

Fig. 4 is a fragmentary elevational view 40 of the shaft supporting upright and associated parts of the propeller stop operating means,

Fig. 5 is a horizontal sectional view taken upon line V—V of Fig. 3,

Fig. 6 is a view substantially similar to the forward portion of Fig. 1 showing a modified form of auxiliary overhead propeller,

Fig. 7 is an enlarged view partially in side 50 elevation and partially broken away of the propeller supporting means of Fig. 6 with a section of the upright removed to reveal shafts and bearings therein,

Fig. 8 is a rear elevational view of the device shown in Fig. 7, and

Fig. 9 is a horizontal sectional view taken upon line IX—IX of Fig. 8.

Referring more in detail to the several views, the present invention contemplates the provision of improved supporting and driving means for an auxiliary overhead propeller particularly serviceable in aeroplanes of the type shown in Fig. 1 wherein the numeral 5 is used to generally indicate the body or fuselage of the aeroplane, said body being provided with the usual empennage 6, wings 7 and supporting wheels 8. A suitable structure 9 is usually provided in the forward end of the body 5 for receiving an engine 10 whose drive shaft 11 projects forwardly of the body and has a main propeller 12 secured thereon for causing forward movement of the aeroplane.

The present invention contemplates the provision of an extension 13 projecting rearwardly from the crank case 14 of the engine 10 and inclosing a rearwardly projecting portion of the drive shaft 11 which may be formed in two sections adapted to be coupled and uncoupled by any desired form of clutch shown at 15 by dotted lines in Fig. 2 and having an operating handle 16.

The rear section of the rearwardly projecting portion of the engine drive shaft 11 is shown at 17 in transverse section in Fig. 3, 85 and it has a worm gear 18 secured thereon meshing with a worm 19 fixed upon the lower end of a vertical shaft 20 journaled within an upright 21. This upright is preferably formed of a pair of longitudinal half 90 section clamped together by means of angle clamps 22 and having mating recesses forming a longitudinal bore within the upright through which the shaft 20 extends and also forming at intervals, in large pockets for 95 reception of collars 23 provided on the shaft 20. The collars 23 are fixed on said shaft and suitable ball bearings 24 are disposed between the upper wall of each pocket and the upper end of each collar 23 for providing an upward end thrust bearing with minimum friction. The upright 21 may be provided with feet 25 bolted or otherwise secured to the floor of the body 5, and a packing 26 is preferably arranged between 100 the meeting faces of the sections of this

upright to guard against entrance of dust within the same and to avoid noisy vibration. The gear case extension 13 is preferably rigidly connected to the upright 21 in any desired manner so as to brace the latter, and the sections of said upright are suitably chambered at this point for accommodating the worm gear 18 and the worm 19 as shown in Fig. 3.

10 In this form of the invention a propeller 27 is fixed upon the projecting upper end of the shaft 20 in a horizontal position and at a suitable elevation. Obviously, when the clutch 15 is thrown in, the propeller 27 will be rotated in the proper direction to exert a desired lifting force upon the aeroplane for assisting in launching or landing of the same, which action of said propeller 27 may be controlled to the desired degree by the 20 speed of the engine.

Means is provided to hold the propeller 27 against rotation when the aeroplane is in flight with the clutch 15 disconnected so that the wind will not rotate said propeller and 25 parts geared thereto and with the blades of the propeller positioned substantially parallel to the longitudinal axis of the aeroplane. This means preferably consists in a vertically movable rod 28 slidably mounted 30 in guides 29 rigid with the upright 21 and provided with a yoke 30 upon its upper end arranged to embrace the rear blade of the propeller 27 when in raised position as shown in Fig. 3. The lower end of the rod 35 28 is formed with a rack 31, and a gear 32 meshes with this rack and is rotatably supported by a depending bracket 33 on the lower guide 29. A crank handle 34 is provided upon gear 32 for rotating the latter 40 whereby the rod 28 may be raised and lowered, and a suitable stop member 35 is arranged to be dropped between adjacent teeth of the gear 32 for holding the gear against rotation and thereby preventing lowering 45 of the rod 28 when it is disposed with the yoke 30 embracing the rear wing of the propeller 27. By rotating crank handle 34 in one direction the rod 28 will be raised to hold the propeller against rotation, and 50 when the stop member 35 is released from gear 32, the rod 20 will lower by its own weight and release the propeller 27.

Referring to the form of the invention shown in Figs. 6 to 9 inclusive, the usual 55 fuselage or body 5' is shown with supporting wheels 8', wings 7' and a motor 10' having its drive shaft 11' projected forwardly of the body 5' with a main propeller 12' secured thereon. In this form of the invention the gear case extension 18' of the engine 10' connects with an inverted substantially L-shaped upright 36 having its upper and shorter arm projecting forwardly and provided with feet 25' upon its lower end 60 bolted or otherwise secured to the floor of

the body 5'. In this form of the invention the upright 36 is also of longitudinal split form or composed of substantially similar longitudinal half sections secured together by screws or bolts 37 and provided with 70 mating recesses forming a longitudinal or central bore for accommodating a vertical shaft 38 within the longer portion of the upright and a horizontal forwardly extending shaft 39 within the shorter portion of 75 said upright. The adjacent ends of the shafts 38 and 39 are intergeared by bevel gears 40 or the like so that rotation is imparted from one to the other, and the forward end of the shaft 39 has a propeller 41 80 fixed thereon in vertical position so as to assist the main propeller 12' in propelling the aeroplane forwardly. The longitudinal bore of the upright 36 is enlarged at intervals to form pockets for reception of the 85 collars 23' upon the shafts 38 and 39, and suitable anti-friction members 24' are disposed between the opposite end walls of these pockets and the ends of the collars 23' to anti-frictionally take up end thrusts in 90 both directions. In this form of the invention a worm 19' is provided upon the lower end of the shaft 38 and it meshes with a worm gear 18' fixed upon the rear end of the engine drive shaft 11'. It will of course 95 be understood that, as is usual in this art, any transmission gearing or additional clutches that are found desirable for the driving and controlling of the propellers may be added or employed, but as they do 100 not form any part of the present invention, they are not shown or described.

It is believed that the construction and operation as well as the advantages of the present invention will be readily understood and appreciated from the foregoing 105 description.

Minor changes may be made without departing from the spirit and scope of the invention as claimed.

What is claimed as new is:—

1. In combination with an aeroplane having a fuselage with a main propeller actuating motor at the forward end thereof, said motor being provided with a rearwardly projecting drive shaft, a dust-proof upright rigidly mounted at the rear end of said shaft, a vertical shaft journaled within said upright and rotatably geared to the first named shaft, an overhead auxiliary propeller operatively connected to the upper end of said second named shaft, means operable by a person within the fuselage to disconnect the second named shaft from the drive shaft, and means operable by the person within the 115 fuselage to releasably maintain the overhead propeller against rotation when said second named shaft is disconnected from the drive shaft, said last named means including a vertically slideable rod having a 120 125 130

yoke upon its upper end arranged to embrace the rear wing of the propeller when said rod is raised.

2. In combination with an aeroplane having a fuselage with a main propeller actuating motor at the forward end thereof, said motor being provided with a rearwardly projecting drive shaft, a dust-proof upright rigidly mounted at the rear end of said shaft, 10 a vertical shaft journaled within said upright and rotatably geared to the first named shaft, an overhead auxiliary propeller operatively connected to the upper end of said second named shaft, means operable by a 15 person within the fuselage to disconnect the second named shaft from the drive shaft, means operable by the person within the fuselage to releasably maintain the overhead propeller against rotation when said second 20 named shaft is disconnected from the drive shaft, said last named means including a vertically slideable rod having a yoke upon its upper end arranged to embrace the rear wing of the propeller when said rod is raised, and hand operated means arranged 25 adjacent and operatively connected to the lower end of said rod for vertically moving the latter.

3. In combination with an aeroplane having a fuselage with a main propeller actuating motor at the forward end thereof, said motor being provided with a rearwardly projecting drive shaft, a dust-proof upright rigidly mounted at the rear end of said shaft, 30 a vertical shaft journaled within said upright and rotatably geared to the first named shaft, an overhead auxiliary propeller operatively connected to the upper end of said second named shaft, means operable by a person within the fuselage to disconnect the second named shaft from the drive shaft, means operable by the person within the fuselage to releasably maintain the overhead propeller against rotation 35 when said second named shaft is disconnected from the drive shaft, said last named means including a vertically slideable rod having a yoke upon its upper end arranged to embrace the rear wing of the propeller 40 when said rod is raised, hand operated means arranged adjacent and operatively connected to the lower end of said rod for vertically moving the latter, said hand operated means including a rotatable gear, and a stop member operable to engage the teeth of said gear whereby the rod is held in raised position 45 with the yoke embracing said propeller blade.

4. In combination with an aeroplane having a fuselage with a main propeller actuating motor at the forward end thereof, said motor being provided with a rearwardly projecting drive shaft, a dust-proof upright rigidly mounted at the rear end of said shaft, 50 a vertical shaft journaled within said up-

right and rotatably geared to the first named shaft, an overhead auxiliary propeller operatively connected to the upper end of said second named shaft, said upright comprising a member formed of longitudinal half sections, a packing disposed between the meeting faces of said half sections, and means to clamp said half sections together. 70

5. In combination with an aeroplane having a fuselage with a main propeller actuating motor at the forward end thereof, said motor being provided with a rearwardly projecting drive shaft, a dust-proof upright rigidly mounted at the rear end of said shaft, a vertical shaft journaled within said upright and rotatably geared to the first named shaft, an overhead auxiliary propeller operatively connected to the upper end of said second named shaft, said upright comprising a member formed of longitudinal half sections, a packing disposed between the meeting faces of said half sections, means to clamp said half sections together, said vertical shaft being provided with collars, said half section being recessed to provide 80 pockets within which said collars are arranged, and thrust bearings arranged between the bearings and the walls of the recesses for anti-frictionally taking up thrusts upon said vertical shaft. 95

6. In combination with an aeroplane having a fuselage with a main propeller actuating motor at the forward end thereof, said motor being provided with a rearwardly projecting drive shaft, a dust-proof upright rigidly mounted at the rear end of said shaft, a vertical shaft journaled within said upright and rotatably geared to the first named shaft, an overhead auxiliary propeller operatively connected to the upper end of said second named shaft, a gear case extension upon the gear case of the motor inclosing the rearwardly projecting portion of the drive shaft, operative connection between the drive shaft and the vertical shaft including 100 intermeshing gears, said upright being chambered for reception of said gears, and said gear case extension forming a closure for said chamber. 105

7. In combination with an aeroplane having a fuselage with a main propeller actuating motor at the forward end thereof, said motor being provided with a rearwardly projecting drive shaft, a dust-proof upright rigidly mounted at the rear end of said shaft, a vertical shaft journaled within said upright and rotatably geared to the first named shaft, an overhead auxiliary propeller operatively connected to the upper end of said second named shaft, a gear case 115 extension upon the gear case of the motor inclosing the rearwardly projecting portion of the drive shaft, operative connection between the drive shaft and the vertical shaft including intermeshing gears, said upright 120 including a stop member operable to engage the teeth of said gear whereby the rod is held in raised position with the yoke embracing said propeller blade. 125

130

being chambered for reception of said gears, and said gear case extension forming a closure for said chamber, said gear case extension being associated with said upright 5 for bracing the same in vertical position.

8. In combination with an aeroplane having a fuselage with a main propeller actuating motor at the forward end thereof, said motor being provided with a rearwardly 10 projecting drive shaft, a dust-proof upright rigidly mounted at the rear end of said shaft, a vertical shaft journaled within said upright and rotatably geared to the first named shaft, an overhead auxiliary propeller operatively connected to the upper end of said 15 second named shaft, said upright being of substantially inverted L-shaped form in elevation and projecting forwardly, and a third horizontally disposed shaft journaled within the upper shorter arm of said upright and 20 operatively geared at its rear end to the upper end of said vertical shaft, the overhead propeller being mounted upon the forward end of said third shaft.
- 25 9. In combination with an aeroplane hav-

ing a fuselage with a main propeller actuating motor at the forward end thereof, said motor being provided with a rearwardly projecting drive shaft, a dust-proof upright rigidly mounted at the rear end of said shaft, 30 a vertical shaft journaled within said upright and rotatably geared to the first named shaft, an overhead auxiliary propeller operatively connected to the upper end of said second named shaft, said upright being of substantially inverted L-shaped form in elevation and projecting forwardly, a third horizontally disposed shaft journaled within the upper shorter arm of said upright and 35 operatively geared at its rear end to the upper end of said vertical shaft, the overhead propeller being mounted upon the forward end of said third shaft, and thrust bearings for the third shaft including collars upon the latter and anti-friction members disposed between said collars and adjacent portions of the upright.

In testimony whereof I affix my signature.

GEORGE H. RIB.
